H. J. BUCK

ANTIFRICTION BEARING FOR GRAVITY CARRIERS

Filed Apr. 19, 1920

INVENTOR

HERMAN J. BUCK

By Paul & Paul

HIS ATTORNEYS.

UNITED STATES PATENT OFFICE.

HERMAN J. BUCK, OF ELLWOOD CITY, PENNSYLVANIA, ASSIGNOR TO MATHEWS GRAVITY CARRIER COMPANY, OF ELLWOOD CITY, PENNSYLVANIA, A CORPORATION OF PENNSYLVANIA.

ANTIFRICTION BEARING FOR GRAVITY CARRIERS.

Application filed April 19, 1920. Serial No. 375,046.

To all whom it may concern:

Be it known that I, HERMAN J. BUCK, a citizen of the United States, resident of Ellwood City, in the county of Lawrence and State of Pennsylvania, have invented certain new and useful Improvements in Anti-friction Bearings for Gravity Carriers, of which the following is a specification.

The present invention relates to improvements in anti-friction bearings for the rolls or conveyer members of gravity carriers, and is an improvement upon the bearing illustrated and described in Letters Patent issued to me September 4th, 1917, No. 1,238,880.

The object of this invention is to simplify and make more convenient for assembling and removal the construction disclosed in my former patent; to provide means for positively locking all parts of the bearing together; to provide means for deflecting dirt and dust away from the bearing, thereby shielding and protecting the same when the carrier is in operation; to provide, in connection with the bearing, an oil pocket or receptacle, which will hold a small amount of oil, and from which pocket the oil will readily work through the bearing while the carrier is in operation; and to provide a bearing in which all walls of the ball race are hardened so that the balls are not in contact with any soft metal surface.

Other objects of the invention will appear from the following detailed description.

The invention consists in various constructions and combinations as herein described and particularly pointed out in the claims.

In the accompanying drawings forming part of this specification,

Figure 1 is a transverse sectional view of a carrier with one of the carrier rolls shown in longitudinal section, a portion of the middle part of the roll being broken away.

Figure 2 is a transverse section on line 2—2 of Figure 1,

Figure 3 is a detail section of the bearing,

Figure 4 is a section of one end of the roll showing the recessed head seated therein,

Figure 5 is a detail showing a modified construction of the outer cup.

Figure 6 is a detail showing the modified construction of the inner cup.

In the drawing, 2, 2 represents the side

rails of the carrier, having slots 3 to receive the rods or axles 4, of the rolls. These rods 55 are preferably secured in the rails by locking bars 5 through which pass bolts 6 to fasten the bars 5 to the rails 2.

7 represents a conveyer or carrier roll, preferably made of light steel tubing and 60 open at each end.

The parts hereinbefore described are substantially like the corresponding parts in my former patent hereinbefore referred to.

A head 8, preferably secured as shown, is 65 arranged in each end of the roll 7 and is secured therein by any suitable means, such as by center punching, riveting or welding. This head is preferably in the form of an annulus having the circular webs 9 and 10 70 united by a transverse web 11. As shown, the outer surface of the web 9 is preferably coincident with the inner surface of the cylinder 7, so that said head may be seated in the end of the cylinder and fit snugly therein. The web 9 is preferably provided with the turned-out flange 9' that butts against the end of the roll.

The web 10 is preferably concentric with the web 9, to which it is united by the web 80 11 formed integrally with the webs 9 and 10, as shown in the drawings. Preferably the web 10 is somewhat shorter than the web 9 and the outer edge of the web 9 is preferably turned down at right angles so as to 85 form a stop or shoulder which comes against the end of the roll when the head is inserted therein. Arranged between the web 10 of the head 8 and the axle or rod 4 is a roller cage or race containing a series of balls 20 90 which provide an anti-friction support for said roll. The cage that I prefer to use is preferably formed of two metal cups 12 and 13, the larger outer cup 12 fitting loosely within the head 8 with its outer wall in contact with the inner wall of the web 10 of said head. The bottom of the cup 12 is formed by an inwardly extending flange 14, having a central opening and its opposite edge is turned outward forming a narrow 100 flange 15. The cup 13 corresponds in shape to the cup 12 and is nested therein, being provided with a bottom 16, also having a central opening that is parallel to the bottom 14 of the cup 12, and with a flange 17 parallel to the flange 15 of the cup 12. The

95 105

cup 13 is of less depth than the cup 12, so that when the cup 13 is nested in the cup 12, with its flange 17 in contact with the flange 15 of the cup 12, an annular ball race is formed between the bottoms 14 and 16 of said cups.

I prefer to provide a sleeve 18 that fits loosely upon the rod or axle 4 and is capable of sliding longitudinally thereon. This 10 sleeve passes through the openings in the bottoms of the cups and it has an annular groove 19 arranged opposite the space between the bottoms of said cups. A series of balls 20 are provided in the ball race formed 15 between said cups and the grooved portion of said sleeve.

The sleeve 18 and the two cups 12 and 13 are preferably case hardened so as to form an annular ball race having all of its walls 20 of hardened steel, thereby permitting the cage and supported roller to rotate upon the sleeve 18 with a minimum amount of friction, and also reducing the wear on the parts of said race to a minimum.

25 After the parts of the bearing are assembled with the balls extending into the annular groove 19 in the sleeve 18, the cups 12 and 13 are preferably locked together by means of a disc of soft metal 21, having a 30 central opening for the passage of the sleeve 18 and with its outer edge crimped or bent over the flanges 15 and 17 of the nested cups, and then bent inward so as to form a flange 22 fitting against the under surface of the 35 flange 15 of the cup 12.

The disc 21 not only locks the nested cups together, but it serves to deflect away from the bearing dust or dirt that might be thrown against it. The space within the cup 40 13 and under the surface of the plate 21, forms an oil pocket or receptacle into which oil may be injected and where it will be held and carried as the device rotates, a considerable portion of the oil working into the ball 45 space between the edge of the bottom 16 of the cup and the outer surface of the sleeve 18, thereby providing lubrication for said bearing.

The sleeve 18, the cups 12 and 13, the locking disc 21 and the series of balls 20 arranged in the race, form a self-contained ball-bearing or anti-friction unit that can be independently assembled and which is readily brought into position in the carrier by slipping it over the end of the rod or axle 4, and into the head 8 in the end of the cylinder or roll 7. When the bearing is thus brought into position in the carrier the cup 12 telescopes into the head 8 fitting within the 55 flange 10 until the turned over part 22 of the locking disc 21 comes into contact with the edge of the flange 10 of the head 8.

When the rod 4 with the sleeve and bearing assembled thereon is put in place in the 60 carrier rails 2, and is locked in this position

by the locking bar 5, the parts cannot separate as longitudinal movement of the sleeve 18 is prevented by reason of the proximity of the end of the sleeve to the inside of the rail 2.

When, however, it is desired for any purpose to take the bearing out of the roll, the locking bar 5 may be removed and the rod 4 lifted out of the notches or recesses in the rails 2. The unitary ball bearing may then be drawn out of the head 8 and removed from the rod or axle by sliding the sleeve 18 longitudinally on said rod.

I find it unnecessary to provide any means for locking the ball bearing in the head 8, as the friction between the outer surface of the cup 12 and the inner surface of the head will be sufficient to cause these parts to move together the cage and the balls traveling around the sleeve 18.

The friction between the balls and the sleeve 18 being less than the friction between the surface of the cup 12 and the head 8, the cage will move with the head and roll, notwithstanding the fact that there is no positive connection between the cup 12 and said head.

The sleeve 18 being free upon the rod 4 may turn thereon, and will do so to such an extent as to change its position on the rod, as pointed out in my said former patent.

While the general construction and arrangement of the parts in this bearing is the same as in the bearing described in my said former patent, the present construction is 100 an improvement over my former bearing in that the nested cups forming the ball race are secured together by means of the soft metal locking plate having its edge turned over the flanges of said cups. This locking plate may readily be removed, should the balls become broken or if for any other purpose it is desired to separate the cups. When the soft metal plate is removed the inner cup 13 may readily be lifted out of the 110 cup 12.

The locking plate also forms a protecting disc or cover for the bearing, and provides an oil receptacle or pocket in which a certain amount of oil may be carried. This oil will 115 work between the inner cup and the disc and lubricate the parts of the bearing.

While I have illustrated and described balls as forming the anti-friction element of the bearing, it will be understood that 120 suitable rollers or cylinders might be substituted for the balls without departing from my invention, and by the term "balls" as used in the specification and claims I include equivalent anti-friction rollers.

While I prefer to form both of the cups 12 and 13 of sheet metal stamped out by suitable dies I do not limit myself to this construction. In Figure 5 I have shown the cup 12 having a bottom 12' formed separate- 130

ly and secured in position in the lower end of the cup. In Figure 6 I have shown the cup 13 in the form of an open cylinder without its upper flange, and the cup 12 with a shoulder 12" on its inner surface forming a seat for the cup 13.

The details of the construction may be varied in many particulars without departing from my invention.

10 I claim as my invention:

1. An anti-friction bearing for gravity carriers comprising a sleeve, a cage surrounding said sleeve and formed of flanged cups nested together with a space between the bottoms of said cups, rotatable members arranged in the race formed between the bottoms of said cups and said sleeve, and means locking the flanges of said cups together, substantially as described.

20 2. An anti-friction bearing for gravity carriers, comprising a sleeve, a cage surrounding said sleeve and formed of flanged cups nested together with a space between the bottoms of the cups, rotatable members arranged in the race formed between the bottoms of said cups and said sleeve, and a locking plate extending across the inner cup and having its edge bent over the cup flanges and locking said cups together, substantially as described.

30 3. A ball bearing for gravity carriers comprising a sleeve, a ball cage surrounding said sleeve and formed of flanged cups nested together with a space between the bottoms of said cups, balls arranged in the race formed between the bottoms of said cups and said sleeve, and means locking the flanges of said cups together.

40 4. A ball bearing for gravity carriers comprising a sleeve, a ball cage surrounding said sleeve and formed of flanged cups nested together, balls arranged in the race between the bottoms of said cups and said sleeve, and a locking plate extending across the inner cup and having its edge bent over the cup flanges and locking said cups together, substantially as described.

50 5. The combination with an axle and a carrier roll having heads recessed around said axle, of anti-friction bearings, each constituting a self-contained unit arranged on said axle, and longitudinally movable thereon to engage it with or disengage it from said roll head, and each bearing formed of a cage consisting of a pair of flanged cups nested together with the open ends of the cups towards the ends of the roll, means securing the flanges of said cups together, and rotatable members arranged in said cage and supporting said cage and the roll head in which said cage is seated.

60 6. The combination with an axle and a carrier roll having heads recessed around said axle, of anti-friction bearings, each constituting a self-contained unit arranged on

said axle, and longitudinally movable thereon to engage it with or disengage it from said roll head, and each bearing formed of a cage consisting of a pair of flanged cups nested together, a locking plate extending across the inner cup and having its edge bent over the cup flanges and locking said cups together, and rotatable members arranged in said cage and supporting said cage and the roll head in which said cage is seated.

7. The combination with an axle and a carrier roll having heads recessed around said axle, of anti-friction bearings, each constituting a self-contained unit arranged on said axle, and longitudinally movable thereon to engage it with or disengage it from said roll head, and each bearing formed of a cage consisting of a pair of flanged cups nested together, and having the open ends of the cups towards the ends of the rolls, a locking plate extending across the inner cup and having its edges bent over the cup flanges and locking said cups together, and rotatable members arranged in said cage and supporting said cage and the roll head in which said cage is seated.

8. An anti-friction bearing for gravity carriers, comprising a sleeve, a cage surrounding said sleeve and formed of cups nested together with a space between the bottoms of said cups, said outer cup being provided with an outwardly turned flange, rotatable members arranged in the race formed between the bottoms of said cups and said sleeve, and a locking plate extending across said cups and having its edge bent over the flange of the outer cup and locking said cups together.

9. The combination with an axle and a carrier roll having heads recessed around said axle, of anti-friction bearings, each constituting a self-contained unit arranged on said axle and longitudinally movable thereon to engage it with or disengage it from said roll head and each bearing formed of a cage consisting of a pair of cups nested together with a space between the bottoms of said cups, the outer cup having a flange at its open end, a locking plate extending across said cups and having its edge bent over the flange of the outer cup and locking said cups together and rotatable members arranged in the race formed between the bottoms of said cups and supporting said cage and the roll head in which said cage is seated.

10. An anti-friction bearing comprising an axle, a cage surrounding said axle, and formed of flanged cups nested together with a space between the cup flanges and between the axle and the interior wall of one of said cups forming a race, anti-friction members arranged in the race, a bearing for the outer cup, and means for locking the flanges of said cups together.

11. An anti-friction bearing comprising an axle, a cage surrounding said axle, and formed of flanged cups nested together with a space between the cup flanges and between the axle and the interior wall of one of said cups forming a race, anti-friction members arranged in the race and a soft metal disc for locking the flanges of said cups together, said disc forming with the cup and axle an oil cavity as shown and described. 10
- In witness whereof, I have hereunto set my hand this 9th day of April, 1920.
- HERMAN J. BUCK.
